F. A. SCHOENL & H. BIEDER,
LUBRICATOR FOR LEAF SPRINGS,
APPLICATION FILED NOV. 22, 1916.

1,222,807.

Patented Apr. 17, 1917.

UNITED STATES PATENT OFFICE.

FRANK A. SCHOENL AND HERMAN BIEDER, OF CLEVELAND, OHIO.

LUBRICATOR FOR LEAF-SPRINGS.

1,222,807.

Specification of Letters Patent. Patented Apr. 17, 1917.

Application filed November 22, 1916. Serial No. 132,832.

To all whom it may concern:

Be it known that we, FRANK A. SCHOENL and HERMAN BIEDER, citizens of the United States, residing at Cleveland, in the county 5 of Cuyahoga and State of Ohio, have invented certain new and useful Improvements in Lubricators for Leaf-Springs, of which the following is a specification.

This invention relates to lubricators for 10 springs, especially leaf springs used on motor vehicles or the like, and it has for its object to provide a simple and efficient device for the purpose stated which can be quickly and easily applied to a spring, and 15 which is capable of adjustment to fit springs of various sizes.

The device comprises a pair of holders or 20 casings containing pads to which oil may be supplied, these holders being applied to opposite sides of the spring and held in place by springs connecting the respective holders.

The invention is illustrated in the accompanying drawing in which:

Figure 1 is a perspective view illustrating 25 the device applied to a spring.

Fig. 2 is a side elevation.

Fig. 3 is a top plan view, partly in section.

Fig. 4 is a detail of one of the holders.

Fig. 5 is a side elevation showing the 30 holder applied to a thick spring.

Referring specifically to the drawings, 6 indicates a leaf spring to which the lubricator is applied. This lubricator comprises a pair of holders each of which consists of a 35 sheet metal plate 7 of substantially diamond shape, or longer in one direction than in a direction perpendicular thereto. The edges of this plate are turned in as indicated at 8, to retain a pad 9, of felt or the like. At two 40 adjacent corners the metal is struck up to form a cup or opening 10 through which oil may be supplied to the pad from an oil can. The remaining corners of each plate have holes 11.

45 In the use of the device, the holders are applied to opposite sides of the spring, and are connected above and below the spring by coiled springs 12 the ends of which are hooked into the openings formed by the cups 50 10 and the holes 11. These springs clamp the pads against the sides of the vehicle spring and retain the holders in position

without interfering with the normal action of the leaf spring, the vibration of which induces a flow of oil from the pads between the 55 contacting faces of the leaves.

For use on a relatively thin spring, as shown in Fig. 2, the holders are placed with their longer axes parallel to the spring. For use on thicker springs, as shown in Fig. 60 5, the holders are placed with their longer axes crosswise of the spring, the coiled springs 12 being changed to the corresponding corners of the holders. In either position, one of the cups 10 is presented upwardly to receive the oil supply which soaks 65 into the pad for the stated purpose.

What we claim as new is:

1. A lubricator for leaf springs, comprising a pair of holders provided with pads 70 and adapted to be applied to opposite sides of the spring, said holders being longer in one direction than another, and connections between the holders engageable therewith at either longer or shorter axes, whereby the 75 holders may be applied to springs of different thicknesses.

2. A lubricator for leaf springs, comprising a holder provided with a pad and adapted to be applied to the side of a spring, said 80 holder having longer and shorter axes, and retaining devices engageable with the holder at either axis, to hold the same on the spring.

3. A lubricator for leaf springs, comprising a holder provided with a pad and adapted 85 to be applied to the side of a spring, said holder having longer and shorter axes, and retaining devices engageable with the holder at either axis, to hold the same on the spring, said holder also having oil supply openings 90 at points corresponding to the different axes.

4. A lubricator for leaf springs, comprising a pair of diamond-shaped holders provided with pads and adapted to be applied to opposite sides of the spring, and retaining 95 springs connecting the opposite holders and engageable with various corners thereof.

In testimony whereof we do affix our signatures in presence of two witnesses.

FRANK A. SCHOENL.
HERMAN BIEDER.

Witnesses:

JOHN A. BOMMHARDT,
S. W. BRAINARD.
